UNITED STATES PATENT OFFICE.

ROBERT T. WEAVER, OF NEW YORK, N. Y.

DESIGN FOR A DOMESTIC WATER-FILTER.

SPECIFICATION forming part of Design No. 34,658, dated June 11, 1901.

Application filed May 9, 1901. Serial No. 59,536. Term of patent 14 years.

To all whom it may concern:

Be it known that I, ROBERT T. WEAVER, a citizen of the United States, and a resident of the city of New York, county of New York, 5 and State of New York, have invented and produced a new and original Design for Domestic Water-Filters, of which the following is a specification.

In the accompanying drawing is shown in 10 side elevation a filter disclosing my new design.

As shown in the drawing, the leading or material feature of the design consists in the plain cylindrical body A, having plain end flanges B B and at its lower part three 15 projections C D E, the first two being located, respectively, adjacent the flanges B B and comprising faucets of ordinary appearance. The central projection E appears merely as 20 a cylindrical hub. At the rear end of the casing or body A there is a hub-like projec-

tion F, while at the front there is a plain cylindrical extension G, of less diameter, having at its outer end a plain flange B' and mounted in its side a faucet H. In the front 25 of the flange B' there is a further hub-like extension, reduced in diameter at its outer end, and at the extreme front of the filter there is a hand-wheel K, the rim of which is formed by the spirally-wound wire or rod K'. 30

Having described my invention, what I claim as new, and desire to secure by Letters Patent, is—

The design for a domestic water-filter substantially as herein shown and described. 35

In testimony whereof I have hereunto subscribed my name.

ROBERT T. WEAVER.
